UNITED STATES PATENT OFFICE.

MAX HERSKOVITZ, OF CHICAGO, ILLINOIS, ASSIGNOR TO PEERLESS LIGHT COMPANY,
OF CHICAGO, ILLINOIS, A CORPORATION OF MAINE.

ELECTRIC-CANDLE SOCKET.

1,397,212.

Specification of Letters Patent. Patented Nov. 15, 1921.

Application filed May 1, 1919. Serial No. 293,957.

To all whom it may concern:

Be it known that I, MAX HERSKOVITZ, a citizen of the United States, residing at Chicago, in the county of Cook and State of Illinois, have invented a new and useful Improvement in Electric-Candle Sockets, of which the following is a specification.

My invention relates more particularly to improvements in socket structures for receiving electric lamps, which are made of such form and appearance as to simulate a candle; and my object is to provide a novel, simple, and economical construction of this general character.

Referring to the accompanying drawing: Figure 1 is a view in vertical sectional elevation of a candle-socket structure embodying my invention, certain parts being shown in section. Fig. 2 is a similar view of a modification thereof. Fig. 3 is a perspective view of one of the members of the structure of Fig. 1; and Fig. 4, a similar view of the corresponding member of the modified construction shown in Fig. 2.

Referring more particularly to Figs. 1 and 3, the main supporting structure of the socket is represented at 5, this member being in the form of a yoke with its arms 6, which are spaced apart, rising upwardly from the cross-piece 7 at its lower end. This yoke is preferably made from sheet metal bent into the desired form, its lower, crosswise-extending portion 7 being preferably of enlarged diameter as represented in Fig. 3 and containing an aperture 8 therethrough which is preferably formed by punching a hole in the section 7 and drawing the metal upwardly to form the annular flange 8^a surrounding the opening 8, the latter being threaded to adapt the yoke 5 to be screwed upon the upper end of a supporting member 9, as for example a bracket-pipe extending from a wall and through which the electric-current-conducting wires extend to the candle-socket, the wires being represented at 10 and 11. The upper ends of the arms 6 are adapted for attachment to the cylindrical casing 12, which may be of fiber or any other suitable insulating material, this connection being made preferably by means of prongs 13 cut from the metal of the arms 6 and extending through slots in the lower portion of the casing 12, the ends of these prongs 13 being then bent against the outer side of the

casing 12 to rigidly clamp the yoke to the casing. The casing 12 is preferably formed of two cylindrical sections 12^a and 12^b, the section 12^b tightly fitting inside the section 12^a at the lower end of the latter to reinforce this part of the casing, the prongs 13 extending through both of these sections. Extending into the upper portion of the casing 12 and secured therein, preferably by screwing into a thread 28 on the section 12^a, is a threaded metal shell 16 adapted to have an electric lamp screwed into it, this shell carrying at its lower end an insulating disk 17 supporting a center electrical contact 18. The electric-current-conducting wires 10 and 11 connect, respectively, with the shell 16 and contact 18. In practice, it is preferred that the entire candle socket structure be provided with relatively short wires connected to the shell 16 and center contact 18 so that in assembling the socket with a supporting structure, as for example the pipe 9, the electric connections between the shell 16 and center contact 18 may be made with the electric wires 80 in the bracket 9 by merely splicing the wires as indicated at 19. The socket structure described is preferably provided as a unitary structure and in assembling it with a support, as for example the bracket 9, the 85 socket structure would be surrounded by a tube, as for example that represented at 20, of a shape and color to represent the body of a candle, this tube being supported in any suitable way, as for example by a cup 21 surrounding the upper end of the pipe 9 and presenting an annular seat 22 at its upper marginal edge into which the lower end of the tube 20 extends, a lamp-shade-supporting member 23, if desired, being also supported on the upper end of the bracket 9. As shown the ornamental saucer-shaped part 23 rests upon a bead 24 provided on the upper end of the bracket, and the cup 21 in turn upon the part 23.

The construction illustrated in Fig. 3 is substantially the same as that shown in Fig. 1 except for the connection of the arms 6 of the yoke 5, with the lower end of the portion 12. In this construction provision is 105 made for adjusting the member 12 and the parts carried thereby, in a vertical direction, and this is accomplished preferably by slotting the upper ends of the arms lengthwise as indicated at 25, and through which 110

slots the screws 26, which screw into openings 27 in the member 12, extend. If desired a ring 28 may be located at the inner surface of the lower end of the member 12 5 and the screws 26 screw into this ring. It will be understood from the foregoing that by loosening the screws 26 the member 12 may be adjusted up and down on the yoke 25 as desired and held in such adjusted position by tightening these screws.

By constructing a candle socket structure in accordance with my invention, a rigid, durable and economical structure may be produced and one complying with all the requirements of use.

It is preferred in practice to introduce cement preferably having current insulating properties into the casing 12 as represented at 29, to embed the electric-wires and preferably to stiffen the casing 12 and arms 6.

While I have illustrated and described certain particular constructions in which my invention is embodied, I do not wish to be understood as intending to limit it thereto, 25 as the same may be variously modified and altered without departing from the spirit of my invention.

What I claim as new and desire to secure by Letters Patent is:

30 1. In an electric socket structure, the combination of a screw shell and a center contact, a casing of fibrous pierceable insulating material in which said shell is located, a supporting member having one of its ends 35 equipped with means for piercing said shell and provided at its opposite end with an apertured portion for attachment to a support and electric-current conducting wires extending therethrough, whereby said shell 40 may be supported at a predetermined height.

2. In an electric socket structure, the combination of a screw shell and a center contact, a casing of fibrous pierceable insulating material in which said shell is located, 45 and a supporting member of yoke form having its free ends equipped with means for piercing said shell, the opposite end of said yoke containing an aperture for attachment to a support and electric-current conducting wires extending therethrough, whereby 50 said shell may be supported at a predetermined height.

3. In an electric socket structure, the combination of a tube of fibrous pierceable insulating material, a screw shell and a center contact solidly secured in said tube, with 55 said tube surrounding said shell, and an arm attached at one end directly to said tube by shell-piercing means carried there-

by, and provided at its opposite ends with means for attaching it to a fixture.

4. In an electric socket structure, the combination of a tube of fibrous pierceable insulating material, a screw shell and a center contact solidly secured in said tube, with 60 said tube surrounding said shell, an arm attached at one end directly to said tube by shell-piercing means carried thereby, and provided at its opposite ends with means for attaching it to a fixture, and wire leads attached to said shell and center contact and extending through the lower end of said tube.

5. An electric socket structure comprising, in combination, a screw shell and a center 75 contact, a casing of pierceable insulating material inclosing said shell, a supporting member provided at one end with prongs for piercing said casing, and means for securing said screw shell and outer casing 80 together.

6. In an electric socket structure, in combination, a fibrous pierceable insulating cylinder, a screw shell within said cylinder, a center contact member, current conducting 85 members, and a cementitious insulating and embedding material surrounding said conducting members to insulate the same and stiffen the structure.

7. In an electric socket structure, in combination, a fibrous pierceable insulating cylinder, a screw shell, a center contact member, current-conducting members, and a cementitious insulating and embedding material surrounding said conducting members to insulate the same and stiffen the structure.

8. In an electric socket structure, in combination, an inner tube, a screw shell adjacent the end portion of said tube, current-conducting members in the tube, cementitious insulating and embedding material within the tube and surrounding said conducting members to insulate the same and stiffen the structure, and an outer tube surrounding said inner tube and extending beyond the latter and engaging the screw shell.

9. In an electric socket structure, in combination, an inner tube, a screw shell adjacent the end portion of said tube, current-conducting members in the tube, cementitious insulating and embedding material within the tube and surrounding said conducting members to insulate the same and stiffen the structure, and an outer tube of fibrous pierceable insulating material surrounding said inner tube and extending beyond the latter and engaging the screw shell.

MAX HERSKOVITZ.
